LEWIS WARRINGTON CHUBB, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed June 30, 1921. Serial No. 481,534.

To all whom it may concern:

Be it known that I, LEWIS WARRINGTON CHUBB, a citizen of the United States, and a resident of Edgewood Park, in the county 5 of Allegheny and State of Pennsylvania, have invented a new and useful Improvement in Systems of Control, of which the following is a specification.

My invention relates to control systems 10 and particularly to such control systems as are adapted to be employed in wireless transmission systems.

One object of my invention is to provide a system of control that shall be simple in 15 construction and efficient in operation and that may be readily adapted for use either in wireless telegraphy or in wireless telephony.

Another object of my invention is to provide 20 an improved wireless transmission system in which the frequency and the amplitude of the alternating component of current in the source of energy may be maintained substantially constant during the signaling 25 and non-signaling periods to obtain stable operation.

Still another object of my invention is to provide a transmission system wherein the 30 antenna circuit may be employed as an absorption circuit, as well as a radiating circuit, thereby permitting the elimination of the expensive separate absorbing circuit which has heretofore been employed.

Other objects of my invention will appear 35 more fully from the details of construction described hereinafter and illustrated in the accompanying drawing.

In the design of control systems for wireless transmission systems, it is desirable to 40 provide a system which maintains the amplitude and frequency of the oscillating currents constant during the signaling and non-signaling periods.

In the present state of the art, the desired 45 result has been partially accomplished by slightly detuning the radiation circuits to form the necessary dots and dashes or by selectively rendering an energy-absorbing circuit effective or non-effective to control 50 the radiation of energy from the radiating circuits.

The former method, however, has the inherent 55 disadvantage of radiating energy at two wave lengths, while the latter method has the disadvantage of employing an addi-

tional circuit requiring expensive apparatus.

According to my invention, I provide a double-antenna system of control wherein the antenna circuits may be employed as an 60 absorbing circuit or as a radiating circuit by so varying the phase of the currents in the antenna circuits that they relatively add or subtract in their effects.

The desired shift in phase of the currents 65 in the radiating antenna circuits may be obtained through the utilization of a phase-splitting device in each antenna circuit. The phase-splitting devices may be of any 70 form well known to the art, such, for example, as static networks comprising condensive and inductive elements.

My invention may best be understood by reference to the accompanying drawings, in 75 which;

Figure 1 is a diagrammatic view of a wireless transmission system embodying my invention;

Fig. 2 is a similar view, but showing an alternative type of phase-splitting device. 80

Referring to Fig. 1, I have shown a two-phase source of high-frequency energy 1 supplying currents to a pair of radiating systems 2 and 3 through transformers 4 and 5 and static networks or so called "mono-cyclic bridges" 6 and 7, respectively. The static networks 6 and 7 comprise, respectively, alternately disposed condensive and inductive elements 8 and 9 in a closed circuit. The reactances of the capacitive and 85 inductive elements 8 and 9, respectively, are preferably equal.

The antenna systems 2 and 3 are shunted across the diagonals 11-12 and 13-14 of the static networks 6 and 7, and comprise, 90 respectively, antennæ 15 and 16, coils 17 and 18, and ground leads 19 and 21. The antennæ 15 and 16 and the coils 17 and 18 may or may not be electro-statically and electro-magnetically coupled, respectively. 95

The phase-splitting devices 6 and 7 are oppositely connected in a circuit 22, which may also include the secondary windings 23 and 24 of the transformers 4 and 5, by conductors 25 and 26 which connect, respectively, points 27 and 28 of the static device 6 to opposite points 29 and 31 of the static device 7.

A shunt connection 32, which extends 100 from conductor 25 to a point 33 on conduc-

2
tor 26, intermediate the secondary windings 23 and 24, is provided, whereby the antennæ systems may be separately energized by the respective phases of the two-phase source of 5 energy 1. The shunt connection 32 may include a switch 34 and a telephone transmitter 35 for wireless telephone signaling, or a key 36, which is shunted around the switch 34 and telephone transmitter 35, for 10 signaling dots and dashes.

The system shown in Fig. 2 differs from that of Fig. 1 only in the arrangement of the condensive and reactive elements in the static networks. The condensive and 15 reactive elements 8' and 9' of each of the networks 6' and 7' are here all connected to a common point 37. Two of the elements 8' and 9' of each network have their free terminals 39, 41 and 42, 43 connected to the 20 antenna systems 2 and 3 respectively. The other two elements 8' and 9' of each network have their free terminals 44, 45 and 46, 47 connected by conductors 25 and 26, respectively, to include the windings 23 and 24 in 25 the circuit 22, as in Fig. 1.

In operation, assuming the shunt connection 32 interrupted by the switch 34 and the key 36, the voltage impressed upon the circuit 22 by the transformers 4 and 5 combine 30 to form a resultant voltage, the value of which is $\sqrt{2}$ times the value of each impressed voltage. By reason of the fact that the static networks 6 and 7 are oppositely connected in the circuit 22, the voltages and 35 consequently the currents in the antenna circuits 2 and 3 are in phase opposition. Thus, the electromagnetic and electrostatic fields set up by the antenna system 2 are neutralized by those set up by the antenna system 3 and substantially no energy is radiated.

Upon depressing the key 36, a circuit is completed through the shunt connection 32 which extends from conductor 25 to the 45 point 33 intermediate the transformer windings 23 and 24 to admit of the separate excitation of the bridges 6 and 7 by the transformers 4 and 5, respectively. The voltages now induced in the respective antenna systems 2 and 3 are thus shifted 45° in opposite directions, whereby they are in quadrature, the resultant radiation therefrom being $\sqrt{2}$ times that of a single antenna system.

55 The operation of the system shown in Fig. 2 is similar to that of Fig. 1, the static networks 6', 7' being the electrical equivalents of those shown in Fig. 1.

As hereinbefore stated, in addition to the 60 signaling of dots and dashes, my system may also be employed for wireless telephone purposes. With the switch 34 closed, the effect of speaking into the transmitting device 35 is to cause corresponding changes in the 65 phase relation of the currents in the radiat-

ing systems 2 and 3, thereby resulting in the radiation of modulated energy.

An advantage of my invention is the provision of a system of control, which causes the radiation of energy at one wave length 70 during the signaling and non-signaling periods, thereby eliminating the compensation or so-called "back-wave".

By the term "static network", I mean to include any system of resistances, 75 capacities and inductances for shifting the phases of currents in two or more circuits connected thereto. The elements may be all static elements, or the impedance of any element may be supplied by means of electronic elements or by means of rotating dynamo-electric machines, provided that no polyphase dynamo-electric machine is employed.

While I have shown only two embodiments of my invention, it is capable of various changes and modifications without departing from the spirit and scope of my invention, as will be obvious to those skilled in the art. I desire, therefore, that only such limitations shall be imposed thereon as are indicated in the appended claims.

I claim as my invention:

1. In a wireless transmission system a 85 pair of static networks, a pair of radiating systems, said radiating systems being across corresponding terminals of said networks, a two-phase source of energy therefor and means for connecting the respective phases 100 of said two-phase source of energy across corresponding remaining terminals of said networks.

2. In a wireless transmission system, a 105 pair of static networks comprising reactive elements substantially resonant to the same frequency, radiating elements connected across corresponding terminals of said networks, said radiating elements being substantially resonant to the same frequency 110 as said networks, a two-phase source of high-frequency energy and means associated therewith for connecting one phase of said two-phase source of energy across remaining terminals of one network and the other phase of said two-phase source of energy 115 across the remaining terminal of the other network.

3. In a wireless transmission system, the combination with a plurality of adjacently 120 disposed antenna systems, each system including a phase-splitting device, and means associated with said phase-splitting devices whereby the phase relation of currents in said antenna systems may be selectively controlled.

4. In a wireless transmission system, the combination with a two-phase high-frequency circuit, of a plurality of proximate 125 radiating elements adapted to be energized from said circuit, and means for selectively 130

varying the phase relation of currents supplied to said radiating elements from said two-phase circuit, whereby the radiation of energy therefrom may be controlled.

- 5 5. In a wireless transmission system, the combination with a two-phase circuit and a plurality of adjacently disposed antennæ, said antennæ being electro-statically coupled, of means associated with said two-phase circuit and said plurality of adjacently disposed antennæ whereby the phase relation of currents supplied to said antennæ may be selectively controlled.
- 10 6. In a wireless transmission system, the combination with a plurality of antennæ and a ground lead for each antennæ, of a plurality of static networks, each ground lead including therein one phase of a static network, a circuit connecting a terminal of

- 20 a second phase of one network to a corresponding terminal of a second phase of another network, a second circuit connecting the remaining terminals of said second phases, and a polyphase source of high-frequency currents included in said second circuit.

- 25 7. In a wireless transmission system, the combination with a pair of adjacently disposed antennæ, of a ground lead for each antenna, a static network included in each ground lead, means for supplying energy to said static networks and means whereby the phase relation of the currents supplied to said plurality of antennæ may be selectively controlled.

- 30 8. In a wireless transmission system, the combination of a pair of antennæ, each antenna being so disposed than an electro-static coupling exists therebetween, a ground lead for each antenna, a plurality of static network, each ground lead including therein one phase of a static network, means for supplying energy to other phases of said static networks and means whereby the 45 phase relation of the currents supplied to said pair of antennæ may be selectively controlled.

- 35 9. In a wireless transmission system, the combination with a pair of antennæ, of a ground lead for each antenna, a pair of static networks, each ground lead including therein one phase of a static network, a circuit connecting a terminal of a second phase of one network to the corresponding 50 terminal of the other, a second circuit connecting the remaining terminals of said static networks, two sources of energy connected in series relation in said second circuit, said sources being substantially in 55 quadrature relation one to the other, and a third circuit extending from said first-named circuit to a point in said second intermediate said sources of energy.

- 60 10. In a wireless transmission system, the combination with a pair of antennæ, a

ground lead for each antenna, each ground lead including therein a monocyclic bridge, a conductor connecting a free terminal of one monocyclic bridge to the corresponding free terminal of the other, a two-phase circuit connecting the remaining free terminals of said monocyclic bridges, and means for causing one phase to energize one antenna and the remaining phase to energize the other antenna.

70 11. In a wireless transmission system, the combination with a pair of antennæ, a ground lead for each antenna, each ground lead including therein a monocyclic bridge, a conductor connecting a free terminal of one monocyclic bridge to the corresponding free terminal of the other monocyclic bridge, a two-phase circuit having sources of energy therein and a circuit extending from said conductor to a point in said first-named circuit intermediate said sources of energy, said circuit including means whereby one phase may be impressed across the terminals of one monocyclic bridge and the remaining phase across the terminals of the other.

75 12. In a wireless transmission system, the combination with a pair of antennæ, a ground lead for each antenna, each ground lead including therein a monocyclic bridge, a conductor connecting a free terminal of one monocyclic bridge to the corresponding free terminal of the other, a two-phase circuit having sources of energy therein, and means comprising a shunt connection extending from said conductor to a point in said first-named circuit intermediate said sources of energy, said circuit including manually-operable means, whereby one phase may be impressed across the terminals of one monocyclic bridge and the remaining phase across the terminals of the other to cause a maximum amount of energy to be radiated from said plurality of antennæ.

80 13. In a wireless transmission system, a pair of static networks, a pair of radiating systems, said radiating systems being connected across corresponding terminals of said networks, a two-phase source of energy therefor, a series circuit including the two phases of said source and the remaining terminals of each of said static networks in series, and a modulating circuit connected across said series circuit from a point intermediate said static networks to a point intermediate the two phases of said source.

85 14. In a wireless transmission system, a pair of static networks comprising reactive elements substantially resonant to the same frequency, radiating elements connected across corresponding terminals of said networks, said radiating elements being substantially resonant to the same frequency as said networks, a two-phase source of high-frequency energy, a series circuit including the two phases of said source and remaining

terminals of each of said static networks in series, and a modulating circuit connected across said series circuit from a point intermediate said static networks to a point intermediate the two phases of said source.

15. In a wireless transmission system, a pair of static networks comprising reactive elements substantially resonant to the same frequency, radiating elements connected across corresponding terminals of said networks, said radiating elements being substantially resonant to the same frequency as said networks, a source of high-frequency currents, means for connecting remaining terminals of both of said static networks in series relation to said source, and modulating means for varying the phase relations of the currents supplied to the respective static networks.

16. An electrical system including trans-

mitting elements having two branches, means for maintaining substantially constant currents in each of said branches and means for varying the phase relationships of said currents.

17. In a wireless transmission system, the combination with a two-phase high-frequency circuit, of a plurality of proximate radiating elements adapted to be energized from said circuit, a variable-impedance device, and means responsive thereto for correspondingly varying the phase relation of currents supplied to said radiating elements from said two-phase circuit, whereby the radiation of energy therefrom may be controlled.

In testimony whereof, I have hereunto subscribed my name this 24th day of June 1921.

LEWIS WARRINGTON CHUBB.
